UNITED STATES PATENT OFFICE

CORNELIUS W. VAN RANST, OF AUBURN, INDIANA, ASSIGNOR, BY MESNE ASSIGNMENTS, TO MANNING & CO., OF CHICAGO, ILLINOIS, A CORPORATION OF ILLINOIS

DESIGN FOR AN INSTRUMENT BOARD FOR AUTOMOBILES

Application filed May 31, 1929. Serial No. 31,472. Term of patent 3½ years.

To all whom it may concern:

Be it known that I, CORNELIUS W. VAN RANST, a citizen of the United States, and a resident of Auburn, county of De Kalb, and State of Indiana, have invented a new, original, and ornamental Design for an Instrument Board for Automobiles, of which the following is a specification, reference being had to the accompanying drawing, forming

a part thereof, and wherein Fig. 1 is a view in front elevation of an instrument board for automobiles, showing my new design, Fig. 2 is a top plan view of the same and Fig. 3 is a view in end elevation thereof.

I claim:

The ornamental design for an instrument board for automobiles substantially as shown.

CORNELIUS W. VAN RANST.
